UNITED STATES PATENT OFFICE.

CHARLES C. SCHARPENBERG, OF BAKERSFIELD, CALIFORNIA.

FLUID-OPERATED WELL-DRILLING APPARATUS.

Application filed October 9, 1922. Serial No. 593,287.

To all whom it may concern:

Be it known that I, CHARLES C. SCHAR-
PENBERG, a citizen of the United States, re-
siding at Bakersfield, in the county of Kern
5 and State of California, have invented cer-
tain new and useful Improvements in Fluid-
Operated Well-Drilling Apparatus, of which
the following is a specification.

My invention relates to the well drilling
10 art, and more particularly to a fluid oper-
ated rotary well drilling apparatus adapted to
be suspended in the well by a non-rotatable
line of pipe.

The principal object of my invention is
15 to provide a device of the described type
which is simple and rugged in construction
and therefore easy to assemble and repair
and reliable under conditions of hard service,
and which is mechanically efficient in opera-
20 tion. A further object of my invention is
to provide means for utilizing a portion of
the power fluid to wash the cuttings away
from the drill bit. A still further object is
to provide means for measuring the force
25 necessary to rotate the drill bit, by means
of the torque reaction upon the non-rotatable
pipe line, this measurement being of use in
determining the rate of speed at which the
drill is fed into the earth formation.

30 With these objects in view, my invention
will now be fully described with reference
to the accompanying drawings, wherein—

Fig. 1 is a longitudinal sectional view of
35 a well showing my drilling apparatus assem-
bled for use.

Fig. 2 is a longitudinal section enlarged
of the motor of my drilling apparatus.

Figs. 3 and 4 are horizontal sections, taken
40 respectively on the lines 3-3 and 4-4 of
Fig. 2.

Fig. 5 is a fragmentary elevation of the
interlocking guide vane rings.

Fig. 6 is a fragmentary elevation of the
runner, showing one set of power vanes and
45 the interlocking sleeves therefor.

Fig. 7 is a fragmentary vertical section of
the motor, showing one set of power vanes
and one set of guide vanes.

Fig. 8 is a part sectional plan, reduced in
50 size, of the torque arm for holding the pipe
line against rotation.

Fig. 9 is a fragmentary detail showing the
form of the vanes.

Fig. 10 is a fragmentary vertical section,
55 enlarged, of a portion of the motor shaft,

showing the means for securing the runner
thereto.

Fig. 11 is a fragmentary vertical section
of the upper end portion of the motor shaft,
showing a modified form of construction
from that shown in Fig. 2.

In the drawings, and referring for the
present to Fig. 1 thereof, the reference nu-
meral 1 designates the well which is being
drilled, and 2 is the line of pipe for sup-
porting the drilling machine. Said pipe line
is suspended from above by the usual means
indicated at 3. The uppermost section or
joint of said pipe line 2 is of square cross
section, as shown at 4 in Figs. 1 and 8, and
this squared portion passes through an arm
5. Rollers 6 are preferably provided in said
arm, to permit the square portion 4 and the
pipe line 2 attached thereto to be raised and
lowered without rotating in said arm. The
outer end of the arm 5 is secured to a sta-
tionary support, not shown, by means of any
suitable form of dynamometer, illustrated in
Fig. 8 as a compression spring 7 interposed
between two tension members 8. By means
of this dynamometer, the torque reaction of
the motor and drill bit may be determined,
and the rate of feed of said drill bit into
the ground regulated accordingly.

The lower end of the pipe line 2 carries
a fluid operated turbine motor comprising
a shell 9, Fig. 2, secured to said pipe 2 and
having a series of vertically spaced sets of
stationary guide vanes 10 alternating with
intervening sets of rotatable power vanes 11.
The guide vanes 10 are secured to or formed
integally with annular rims 12. Said rims fit
snugly within the shell 9, and are wider than
the vanes 10; and they are locked together
against rotation by means of interfitting
tongues 13 formed in their adjacent edges,
as shown in Fig. 5. The lowermost rim is
secured to the shell 9 by any suitable means,
as for example a feather or key 14, Fig. 2.

The power vanes 11 are secured to or
formed integrally with hubs 15, which fit
snugly upon a rotatable central shaft 16.
Said hubs 15 are interlocked by tongues 17,
Fig. 6, in a manner similar to the rims 12
of the guide vanes 10. The lowermost hub
15 is similarly interlocked with a collar 18,
Fig. 10, which is secured to the shaft both
by a feather 19 and a split ring 20, the lat-
ter fitting within a groove in said shaft, as
shown. This construction enables the sets of

vanes to be assembled from the upper end of the shell 9, which can therefore be made in one piece.

Both the stationary guide vanes 10 and 5 the rotatable runner vanes 11 may be of any suitable form, but are preferably of parabolic section, as shown in Figs. 6, 7 and 9, to produce the necessary changes of direction in the fluid stream with the least possible 10 resistance and shock. The inclination of the rotatable vanes is, of course, opposite to that of the stationary vanes, as shown. By means of this parabolic form of the vanes, I am able to get the greatest possible efficiency from the device.

The rotatable runner shaft 16 is mounted in suitable radial and end-thrust bearings 21, Fig. 2, supported by spiders 22 carried by the shell 9. The lower end of said shaft 20 projects below the lower end of said shell and carries the drill bit 23. Said shaft 16 is hollow, and is provided with a funnel shaped open upper end 24, exposed to the incoming stream of fluid from the pipe line 2. The bore 25 of said shaft 16 communicates with a passage 26 extending through the drill bit 23. Thus a portion 25 of the fluid is diverted through the passages 25 and 26 and issues from the drill bit 23 in the form of a jet to wash away the cuttings and improve the action of said drill bit. The main body of fluid passes through the alternate sets of fixed and movable vanes, rotating the shaft 16 and the drill 30 bit 23, and issues from the lower end of the shell 9. The entire spent fluid then passes up through the well, outside the shell 9 and the pipe line 2, carrying with it the cuttings and muck and removing them from 35 the well. A connection is shown at 27 in Fig. 1 for supplying the fluid, under suitable pressure, to the pipe line 2 at the surface of the ground.

Provision is made for lubricating the 45 bearings 21 of the shaft 16, comprising a cylinder 28, Fig. 2, open at the top to the fluid pressure in the pipe line 2, and having a slidable piston 29. When the apparatus is assembled prior to beginning the 50 drilling operation the cylinder 28 is filled with lubricant, below the piston 29, as shown at 29', and said lubricant is subsequently forced, by the fluid pressure above said piston, through suitably disposed pipes 55 or ducts 30 to the shaft bearings 21. Suitable covers or housings 31 are provided for excluding the working fluid from said bearings.

A slight modification of my device is 60 shown in Fig. 11. In this form the turbine shaft 16 is closed at its upper end 16', which lies entirely within the housing 31 of the upper bearing 21, and said shaft is provided with one or more openings 32 be- 65 low said upper bearing, through which the

pressure fluid may enter the bore 25 of said shaft. This construction simplifies the upper shaft bearing structure, rendering more certain the exclusion of the pressure fluid therefrom. It also allows the diverting 70 openings 32 to be made at any desired point in the length of the shaft 16, so that any desired pressure of the diverted fluid in the drill bit passage 26 may be obtained.

I claim:—

1. A well drilling apparatus comprising a shell non-rotatably suspended within the well; a vertically disposed rotatable hollow shaft within said shell; a plurality of vanes carried by said shaft; a drill bit 80 carried by the projecting lower end of said shaft, said drill bit having a fluid passage communicating with the bore of said shaft and leading to the cutting face of said drill bit, and said shaft having a closed upper end and openings in its wall in the region of said vanes; and means for passing a stream of fluid under pressure through said shell to contact with said vanes to rotate said shaft, a portion of said fluid being diverted through said openings and the bore of said shaft to the cutting face of said drill bit.

2. A well drilling apparatus comprising a shell non-rotatably suspended within the well; means for passing a stream of fluid under pressure through said shell; a rotatable shaft within said shell; a plurality of adjacent sleeves surrounding said shaft; means for securing said sleeves upon said shaft; a set of power vanes projecting outwardly from each sleeve; a plurality of adjacent rings fitted within said shell; means for securing said rings to said shell; a set of guide vanes projecting inwardly from each ring and lying between adjacent sets of power vanes, said guide vanes being so disposed as to direct the fluid stream against said power vanes to cause the rotation of said shaft; and a drill bit carried by the 100 lower projecting end of said shaft.

3. A well drilling apparatus comprising a shell non-rotatably suspended within the well; means for passing a stream of fluid under pressure through said shell; a rotatable hollow shaft within said shell, the bore of said shaft being open to the fluid within said shell; a drill bit carried by the projecting end of said shaft, said drill bit having a fluid passage communicating with the bore 115 of said shaft and leading to the cutting face of said drill bit; a plurality of adjacent sleeves mounted upon said shaft for rotation therewith; a set of power vanes projecting outwardly from each sleeve; a plurality of adjacent stationary rings fitted within said shell; and a set of guide vanes projecting inwardly from each ring and lying between adjacent sets of power vanes, 120 said guide vanes being so disposed as to 125

direct the fluid stream against said power vanes to cause the rotation of said shaft.

4. A well drilling apparatus comprising a shell non-rotatably suspended within the well; means for passing a stream of fluid under pressure through said shell; a rotatable shaft within said shell; a plurality of interlocking sleeves surrounding said shaft, one of said sleeves being fixed upon 10 said shaft; a set of power vanes projecting outwardly from each sleeve; a plurality of interlocking rings fitted within said shell, one of said rings being secured to said shell; a set of guide vanes projecting inwardly 15 from each ring and lying between adjacent sets of power vanes, said guide vanes being so disposed as to direct the fluid stream against said power vanes to cause the rotation of said shaft; and a drill bit carried 20 by the lower projecting end of said shaft.
5. A well drilling apparatus comprising a shell non-rotatably suspended within the well; means for passing a stream of fluid under pressure through said shell; a rotatable shaft within said shell; a plurality of interlocking sleeves surrounding said shaft, the lowermost of said sleeves being fixed upon said shaft; a set of power vanes 25 projecting outwardly from each sleeve; a plurality of interlocking rings fitted within said shell, the lowermost ring being secured to said shell; a set of guide vanes projecting inwardly from each ring and lying 30 between adjacent sets of power vanes, said guide vanes being so disposed as to direct the fluid stream against said power vanes to cause the rotation of said shaft; and a drill bit carried by the lower projecting end of said shaft.

6. A well drilling apparatus comprising a shell non-rotatably suspended within the well; a rotatable shaft journaled within said shell; a plurality of vanes carried by said shaft within the shell; means for directing a stream of fluid under pressure against 40 said vanes to rotate said shaft; and means for lubricating the journals of said shaft comprising a cylinder adapted to contain a supply of lubricant and open at one end to the fluid pressure within the shell, a piston in said cylinder for separating the lubricant from the pressure fluid, and a pipe connecting the lubricant-containing end of said cylinder with the bearings of said shaft.

7. A well drilling apparatus comprising a shell non-rotatably suspended within the well; a rotatable hollow shaft journaled within said shell; a drill bit carried by the projecting end of said shaft; a plurality of vanes carried by said shaft within the shell; means for directing a stream of fluid under pressure against said vanes to rotate said shaft; means for diverting a portion of said fluid stream through said hollow shaft to the cutting face of said drill bit to carry 55 off the cuttings therefrom; and means for lubricating the journals of said shaft comprising a cylinder adapted to contain a supply of lubricant and open at one end to the fluid pressure within the shell; a piston 60 in said cylinder for separating the lubricant from the pressure fluid; and a pipe connecting the lubricant-containing end of said cylinder with the bearings of said shaft.

In testimony whereof I have signed my 75 name to this specification.

CHARLES C. SCHARPENBERG.
